Oscar E. Briggs

UNITED STATES PATENT OFFICE.

OSCAR E. BRIGGS, OF BINGHAMTON, NEW YORK.

BRACKET-SEAT.

SPECIFICATION forming part of Letters Patent No. 272,522, dated February 20, 1883.

Application filed June 30, 1881. (Model.)

To all whom it may concern:

Be it known that I, OSCAR E. BRIGGS, of Binghamton, in the county of Broome and State of New York, have invented certain new and useful Improvements in Bracket-Seats, of which the following is a specification.

The invention relates to a folding seat.

Figure 1 is a front view with the seat folded. Fig. 2 is a plan view with the seat in position for being occupied. Fig. 3 is a vertical section taken centrally of the seat. Figs. 4 and 5 are detached views.

A represents a vertical board or the back of a school-desk having my invention applied thereto.

A' is a circular recess cut in the front face of the board.

A² is a circular seat secured, by means of a pivot, b', to a bracket-arm, B, which is hinged at b to a forked or slotted plate or arm, consisting in this instance of two bars or arms, C C, hinged to the upright board A at c. The bracket B may be cast in one piece or formed in two parts firmly united, as indicated in Fig. 3.

D is a brace pivoted to the board A at d, and to the bracket B at d'. The brace is slotted at its lower end, where it carries a latch-piece, F f, pivoted at f'.

D' is a spring secured to the supporting-wall and pressing outward against the brace D, thus forcing the seat outward and upward and facilitating its disengagement from the recess and raising it into position.

f² is a lip projecting from the upperend of the latch-piece, and serving as a stop to regulate the inward throw of the part F of the latch-piece when actuated by a tongue-spring, f³.

E is a locking-link pivoted at e', preferably by the same pivot which unites the bracket-piece B to the frame C C, and having its lower end bent at right angles, as at E'. (See Fig. 4.)

E² is a spring guard, attached at its lower end to the upright board A, with its upper end resting upon the brace D, in such position as to confine the arm E' of the locking-link in close contact with the rear face of brace D.

G is a metal plate, secured to board A immediately below the recess A'.

H is a knob, provided with a shank, h h', and located in an opening in the plate G, the portion h' passing through a hole in the lower end, f, of the locking-latch.

I is a latch reciprocating vertically upon the inner face of plate G, and thrown upward by the spiral spring i².

i' is a stem projecting from latch I into the path of a tripping-jaw, i, attached to the shank h.

When the seat is in the position shown in Fig. 3 the arm E' of link E engages with the locking-lever F and retains the bracket B and frame C C in line with each other, and thus supports the seat A².

When it is desired to let the seat down the operator thrusts the knob H and its attached shanks inward, thus tripping the locking-lever and releasing link E, which permits the bracket and frame to fold up and the seat to swing downward into the recess A' until the locking-latch I enters the groove a, which extends around the seat, thus holding the parts in position.

When it is desired to raise the seat the operator turns knob H and tripping-jaw i so as to withdraw the latch from groove a, when the seat is forced outward and upward by the spring D' into the position shown in Figs. 2 and 3, thus thrusting down arm E', which will engage with the locking-latch, as shown in Fig. 3.

What I claim is—

1. The combination, with the supporting-wall A, bracket B, seat A², and link C C, hinged to said wall and bracket, of the brace D, hinged to the bracket and to the wall A, catch F, and spring f³, by which said bar can be secured and released, spring E², and knob H for operating said catch, substantially as set forth.

2. The combination, with the supporting-wall A, bracket B, seat A², link C C, hinged to said wall and bracket, and brace D, hinged to said wall and seat, of the spring D', whereby the seat is forced outward, substantially as set forth.

3. The combination, with the catch F, which holds the seat open, and the catch I, which holds the seat shut, of the knob H, having the tripping device i, whereby the catch I is disengaged when the knob is rotated, and movable in the direction of its axis to trip the catch F, substantially as set forth.

OSCAR E. BRIGGS.
